UNITED STATES PATENT OFFICE.

JOHN THOMAS SCHAAFF, OF WASHINGTON, DISTRICT OF COLUMBIA.

PAPER-PERFORATING MACHINE.

1,134,018.

Specification of Letters Patent. Patented Mar. 30, 1915.

Application filed July 21, 1914. Serial No. 852,138.

To all whom it may concern:

Be it known that I, JOHN T. SCHAAFF, a citizen of the United States, residing at Washington, District of Columbia, have invented certain new and useful Improvements in Paper-Perforating Machines, of which the following is a description, reference being had to the accompanying drawing and to the figures of reference marked 10 thereon.

The object of this invention is to provide a simple, cheap, durable and efficient punch for perforating strips of paper or cards for any purpose whatsoever and to limit the 15 manual labor necessary to be performed thereon to the positioning of a light part and the closing of an electric circuit. I use but twelve punches and twelve keys for operating them which are sufficient to punch 20 all holes without either shifting or using combinations. I also arrange the keys so that it is unnecessary to move the hand around over the key board as a slight movement of each finger enables it to reach any 25 key properly operated by that finger.

In the punches now in general use, the "field" on the card being punched and all the fields to be punched are hidden from view. I provide an index card carrier capable of receiving a strip cut from a card of the kind being punched. The card carrier and card move along with the card being punched, and a fixed pointer indicates the column which will be punched at the 35 next key depression. This makes greatly for accuracy. As a further means for eliminating error, I provide a simple rheostat and ordinarily allow only enough current to energize the magnet to punch a single hole 40 at one time. Hence if two keys are depressed simultaneously the power is insufficient to force the punches through the paper and a very fruitful source of error is eliminated.

45 As the operator does not have to pound the keys but simply apply a light pressure the nerves are much less disturbed than with the hand power punch. This also makes for accuracy. And the location of the keys 50 where they are easily reached while the arm is held in a natural position is a further material help.

55 While I do not limit myself to the use of one magnet, one circuit and one pair of contact points, in the preferred form of my

device as applied to a punch for tabulator record cards, I have not found it necessary or desirable to use more.

Of the drawings herewith, Figure 1, is a perspective view of the machine. Fig. 2, 60 is a right to left section, through the center of the machine. Fig. 3 is a modification of the slide bar. Fig. 4, is a fore and aft section on a line just to the right of the line of punches. Fig. 5, shows a form of escape- 65 ment well suited to my present device. Fig. 6, shows a form of carriage skip arrangement somewhat similar to that used in some typewriting machines. Fig. 7, shows a top plan view of the key-levers, slide bars, 70 punch levers, push fingers, and punches and Fig. 8 represents a modified form of guide and support for the left-hand end of the slide bars.

The key-levers 3, over-lie the contact 75 frame 27, of the contact mechanism and when a key 3 is depressed, the contact frame 27 is carried down, rocking shaft 25 on its trunnions and through arm 29 carried by shaft 25, forces the end of contact arm 30, 80 against insulating block 31, carried by contact spring 32, bringing its contact point against contact point 33, which is carried by a support capable of yielding slightly under pressure. Arm 34 of the motor-plate 85 15 overlies the free end of arm 30, and when the motor-plate 15, is brought down by the magnet 16, arm 34 strikes the free end of arm 30, forcing it below the block 31, and permitting spring 32 to withdraw its contact point from point 33, breaking the electric circuit, and thus de-energizing the magnet 16, whereupon spring 65 raises the motor-plate 15 to its position of rest. 90

95 Mounted on the horizontal arm 100 of key-levers 3 are plates 4, having an inclined cam surface which engage studs 5 of slide bars 6 and when a key 3, is depressed, a bar 6 is cammed toward the left, bringing its bent end 7, against the upright arm of 100 push finger 8, which is pivoted at 10 to punch lever 11, which lever is fulcrumed at 12 and overlies punches 13.

When a push finger 8 is turned toward the left on its pivot 10, it is brought under 105 the edge of motor-plate 15 and receives movement therefrom when the magnet 16, is energized. When the magnet 16 has depressed the motor-plate 15 sufficiently to operate the punch 13, the motor-plate arm or 110

extension 34, has carried bar 30, out of engagement with block 31, and the contact points separate, and motor plate 15, under the pull of spring 65 resumes its position of rest, and when key-lever 3 is released, slide bar 6 is cammed toward the right, when the lower edge of the bent end 7, of slide bar 6, takes against the arm 9, of the push finger 8, rocking it on its pivot 10, and withdrawing the push finger 8 from under the motor-plate 15, when another key may be depressed for punching.

In Fig. 3, I have shown a modification of the slide-bar as an interposing member. This slide-bar is connected at one end by a pin and fork connection with the punch lever, and is connected to, and is moved by the key-lever in the same manner as is the slide-bar in Fig. 2. Its end which is associated with the punch lever rests normally out of the path of the movement of the motor-plate. Upon the depression of the key-lever, however, it is moved to the left until in a position to receive movement from the motor-plate and through the punch-lever to operate the punch.

To facilitate assembling and to prevent the punches 13 from being forced up out of the guide plate 14, in case it should become necessary to remove the punch-levers 11, I prefer to mill a flat surface on the upper portion of the punches 13, carrying such flat surface to a point about $\frac{1}{2}$ of an inch below the lower surface of plate 75, when the punch levers 11 are in position. Then, when the punch levers are removed, shoulder 76 takes against plate 75 and the punch cannot be forced out by its spring. It is sometimes desirable to skip over one or more "fields" without perforating therein. For this purpose I provide a skip or release key 48 carrying an arm 49 having a hooked end 61 which, when key 48 is depressed, moves into the field of travel of one or other of the movable stops 59. The arm 49 overlies end 46 of the release lever 44, and when the release key 48 is depressed, end 46 is carried down and end 45 rises under the movable end of the stepping dog 47, raising it out of engagement with wheel 43, and the carriage is free to move toward the left until one of the stops 59 comes into engagement with the hook 61, or until the carriage, under the pull of the motor spring (in spring box 52 shown in dotted line in Fig. 4 and being of a well known form employed in typewriters, &c.) has reached the limit of its movement to the left.

In Fig. 2, the right-hand ends of slide bars 6, are guided in a comb 78 secured to the housing 2. The slide bars 6 are prevented from rising out of this comb by a bar 80. The bar 80 has a slotted hole at one end for receiving a screw, and a notch at the other end for the same purpose; thus by

loosening these two screws, the bar 80 may be moved slightly endwise and swung up, that the slide bars may be removed. A similar arrangement could and probably would be used at the left-hand end of slide bars 6, but in the drawings at 77 in Figs. 7 and 8, I have shown a screw machine piece which answers the purpose very well.

Any suitable form of spring motor and escapement may be used for moving the carriage to the left step by step, and I have shown one form of each well known in the typewriter art. The throw of the escapement dog rocker 39 may be regulated by locating the ear 35, on the motor plate 15, nearer to or farther from the motor shaft 17. As will be seen the escapement dog rocker 39, through link 37, receives movement from the motor plate 15, but may be operated from the motor direct.

When the copy is uniform as in the Money Order Division of the Post Office Department, a simple clip such as is shown mounted on the housing 2, might be used to advantage. In this clip 96, 96 are bent wires threaded into the housing; 97, 97 are coiled springs surrounding wires 96; and 95 is a plate sliding freely on wire 96 and yieldingly held by springs 97 against the bent ends of 96.

Cam plates 4, are provided with a dwell at both the upper and lower ends of the cam surface. I do this because in practice, I have found it desirable to have push finger 8, reach the full limit of its movement under the motor plate and stop before the contact points are brought together. The dwell at the lower end of cam surface is a convenient means of taking care of any slight irregularity in the height of the horizontal arms 100 of key levers 3.

In this description, I have several times spoken of a card "carriage" 51. The term carriage is somewhat misleading as the card is simply held in position by the projections 89 and 90 secured to opposite ends of the feed rack 56, 57.

The reference numerals 85 and 86 indicate cushion stops for the motor plate; 83 is a spark reducing coil; 81, 82 and 84 are the parts of a rheostat of a well known form, and 87 is a cushion stop for the punch levers 11.

1 is the main frame; 2 the housing; 18 and 19 are motor shaft journals; 20 is the motor shaft arm; 21 the motor armature, which has an adjustable screw eye 22; its lock-nut 23; shoulder screw 24 for connecting the motor 16 to the motor shaft arm 20.

I have not shown journals for the contact frame shaft 25, but it will be understood that it is journaled in lugs carried by the housing. 36 is a pivot rivet connecting the escapement link 37 with the ear 35.

38 is an arm carried by the escapement

dog rocker 39 with which the link 37 is associated for imparting movement to the rocker.

42 is a block for limiting the movement of 5 the stepping dog 47 toward the left, Fig. 5.

51 is one of two narrow plates which are parts of 89 and 90, and slide in two grooves in the bed plate and support the rack 56, 57, and the card carrier bail 101, 102 and 64. 10 101 and 102 being the two ends and 64 the connecting bar of said bail.

54 is the escapement shaft.

In order that the parts 51 may move freely in the grooves in the bed plate 1, I 15 carry the weight of the bail 101, 102 and the index card carrier on an antifriction wheel 66, carried on support 67, held to the housing 2 by two screws 68.

69 are the key lever guide rods, and 20 70 are springs for restoring the key levers to their position of rest.

71 and 72 are felt cushions for the key levers.

73 is a guide pin for the release key 48, 25 that key having no horizontal arm to be guided by comb 74 as have all the key levers 3.

88 is a handle used in moving the carriage 51 to the right. 91 and 92 are stops limiting the travel of the carriage 51, to the right and left; 93 is an adjusting screw and 94 a holding screw for the left-hand stop.

98 is a switch.

99 is a supporting bar for the motor shaft 35 and the punch lever fulcrums.

It will be understood, that while I have shown my invention as applied to a punching device, I do not wish to limit its use to such a machine.

40 Having thus described my invention, what I claim as new and wish to secure by Letters Patent is:

1. In a perforating machine, the combination of a finger key, a punch, a punch guide 45 and a stationary die registering with the punch, a normally inactive electro-magnetic motor device arranged in a normally open circuit, a source of electric supply in said circuit and a pair of contacts normally spaced apart also in said circuit, means movable from its normal position of rest by the depression of the finger key for closing the said circuit at the said contacts whereupon the said motor device becomes energized, 50 means movable by the said motor device for actuating the punch and for effecting the deenergization of the said motor device immediately thereafter and in advance of any return movement of the key toward its normal position of rest, whereupon the said motor device becomes inactive and remains inactive till another key depression whether the then pressure of the finger upon the key be maintained or not.

55 2. In a perforating machine, the combina-

tion of a plurality of punches, a plurality of finger keys one for each punch, means controlled by the finger keys for selecting the punch or punches to be operated, a stationary die plate and a punch 70 guide both rigidly secured to the frame of the machine, a normally inactive electro-magnetic motor device arranged in a normally open circuit, a source of electric supply and a pair of contacts normally 75 spaced apart also in said circuit, means movable from its normal position of rest by any of said finger keys to close the said contacts, whereupon the said motor device becomes energized, and means movable by 80 the said motor device for operating any one or more of said punches at the same time as desired, and immediately thereafter effecting the deenergization of the said motor device in advance of any return movement 85 of the finger key toward its normal position of rest, said motor device thereafter remaining inactive until another depression of any of said finger keys.

3. In a perforating machine, the combination of a punch, a finger key, an electro-magnet arranged in a normally open circuit, said electro-magnet comprising a fixed part and a reciprocating part, a single pair of contacts, normally spaced apart, in said 95 circuit, one of said contacts having a normal position to which it tends to return when displaced, means operated by the key to close the contacts whereupon the magnet becomes energized, and means movable independently of any further movement of the key, operated by the magnet, for operating the punch and for releasing said contact from its key control, thus permitting said contact to return toward its normal position of open circuit and the magnet to become deenergized in advance of any return movement of the key toward its normal position of rest.

4. In a perforating machine the combination of a punch, a pivoted lever extending across the punch for operating it; a finger key, means for returning said key when displaced to its normal position of rest, a normally inactive motor, a motor plate operated by the motor, an interposing member suitably supported and normally out of the path of movement of the motor plate, said interposing member being connected with the key and adapted to be moved by the key, upon a depression of the key, into a position between the motor plate and the punch actuating lever, means normally controlled by the key to cause the motor to operate the motor plate to effect movement of the punch 110 actuating lever and to disconnect the said motor controlling means from the finger key, whereupon said motor controlling means resumes its normal position and the motor thereupon becomes inactive in ad- 115 120 125 130 135

vance of the release of the key and remains inactive till another key depression.

5. In a perforating machine, the combination of a finger key and means associated with it for restoring it when displaced to its normal position of rest, a normally inactive motor, a punch, a punch actuating lever, a motor plate actuated by the motor, an interposing member, said key having integral with it an extension serving as a cam to transmit reciprocal motion in a plane other than that of the key to the interposing member, said interposing member being suitably supported and lying normally out of the path of movement of the motor plate and in engagement with said key extension and adapted to be moved thereby, upon the depression of the key, into the path of movement of the motor plate to receive movement therefrom independently of the movement of the key and to transmit motion so received to the punch actuating lever; means normally controlled by the finger key to cause the motor to operate the motor plate, said motor plate thereupon operating the interposing member and disconnecting the motor controlling means from the finger key and thus permitting the motor controlling means automatically to return toward its normal position of rest and thereby to deenergize the motor after its having once actuated the motor plate and the motor becomes thereupon again inactive in advance of any return movement of the finger key toward its normal position of rest and remains inactive till another key depressing.

6. In a key controlled mechanism the combination of a finger key, a spring associated with said key for restoring it when displaced to its normal position of rest, an operated part, a normally inactive motor, a motor plate actuated by the motor, means controlled by the key for causing the motor to be actuated, an interposing member in normal engagement with the key and adapted to receive motion therefrom and being normally out of the path of movement of the motor plate; said key being adapted upon its depression to impart to the interposing member an endwise sliding motion, thereby impelling the interposing member into a position between the motor plate and the operated part where said interposing member will receive movement from the motor plate independently of the key and impart motion so received to the operated part; said motor plate being adapted when operated by the motor, to disconnect the key from the motor controlling means, after having once operated the operated part, in advance of any return movement of the finger key toward its normal position of rest.

7. In a key controlled mechanism the combination of a finger key, a spring associated

with said key for restoring it when displaced to its normal position of rest, an operated part, a normally inactive motor, a motor plate operated by the motor, means controlled by the key for causing the motor to be actuated, an interposing member connected to the finger key and adapted to receive motion therefrom and being normally out of the path of movement of the motor plate; said key being adapted upon its depression to impart to the interposing member an endwise sliding motion, thereby impelling the interposing member into a position between the motor plate and the operated part where said interposing member will receive motion from the motor plate independently of the key and impart motion so received to the operated part; said motor plate having integral with it an extension for disconnecting the finger key from the motor controlling means, upon the operation of the motor, thus permitting the motor controlling means to return to its normal position of rest in advance of any return movement of the key toward its normal position of rest; said finger key being adapted to again restore the interposing member to its normal position of rest upon the release of the key.

8. In a perforating machine the combination of a finger key, means for restoring said key when displaced to its normal position of rest, a punch, a punch actuating lever, a normally inactive motor, a motor plate actuated by the motor, means controlled by the key for causing the motor to be actuated, an interposing member suitably supported above the finger key proper, connected to the finger key and adapted to receive an endwise sliding motion therefrom and lying normally out of the path of movement of the motor plate; said key being adapted upon its depression to impart to the interposing member an endwise sliding motion, thereby impelling the interposing member into a position between the motor plate and the punch actuating lever where said interposing member will receive motion from the motor plate independently of the finger key and operate the lever which operates the punch; said motor plate immediately thereafter disconnecting the motor controlling means from the finger key and the motor is deenergized in advance of the release of the key.

9. In a perforating machine the combination of a finger key, a punch, a punch actuating lever, a normally inactive motor, a motor plate actuated by the motor, means controlled by the key for causing the motor to be actuated, an interposing member in engagement with the key and adapted to receive an endwise sliding motion therefrom and being normally out of the path of movement of the motor plate; said key being adapted upon its depression to impel the in-

terposing member into a position where it will be moved by the motor plate independently of the key and impart motion so received to the punch actuating lever to operate the punch; said motor plate thereupon disconnecting the finger key from said motor controlling means in advance of any return movement of the key toward its normal position of rest and the motor thereupon be-

10 comes deenergized.

10. In a perforating machine, the combination of a finger key, a spring associated with said key for restoring it when displaced to its normal position of rest, a punch, a 15 punch actuating lever, a normally inactive motor, a motor plate operated by the motor, means controlled by the key for causing the motor to be actuated, an interposing member loosely supported adjacent its two ends upon 20 suitable supports and extending across the plane of movement of the key and in engagement therewith and adapted to receive motion therefrom, and being normally out of the path of movement of the motor 25 plate; said key being adapted upon its depression to impart to the interposing member an endwise sliding motion, thereby impelling the interposing member into a position between the motor plate and the punch 30 actuating lever, where said interposing member will receive movement from the motor plate independently of the key and impart motion so received to the lever to actuate the punch; and means thereupon acting, operated by the motor, for disconnecting the key 35 from the motor controlling means in advance of any return movement of the key toward its normal position of rest.

11. In a perforating machine the combination of a finger key, a spring associated with said key for restoring it when displaced to its normal position of rest, a punch, a punch actuating lever, a normally inactive motor, a motor plate actuated by 45 the motor, means controlled by the key for causing the motor to be actuated, an interposing member suitably supported and extending across and above the key, said key having an extension integral with it and in 50 engagement with the interposing member adjacent to their lines of intersection and adapted upon the depression of the key to move the interposing member into a position between the motor plate and the punch 55 actuating lever, where the interposing member will receive movement from the motor plate independently of the key and impart motion so received to the lever to actuate the punch; said motor plate having integral 60 with it an extension for disconnecting the key from the motor controlling means in advance of any return movement of the key toward its normal position of rest, whereupon said motor will immediately become 65 inactive and remain inactive till another

key depressing; said key extension being also adapted, upon the release of the key to restore the interposing member to its normal position of rest.

12. In a key controlled mechanism the combination of a finger key and an operated part, an electrically operated power mechanism arranged in a normally open circuit, circuit closing means arranged to be operated by the key to close the circuit, an interposing member directly connected to the key and normally out of the path of movement of the power mechanism, said interposing member being adapted to be given an endwise movement by the key into a position where it will receive motion from the power mechanism independently of the key and transmit motion so received to the operated part; said power mechanism also being adapted to disconnect the key from the circuit closing means in advance of any return movement of the key toward its normal position of rest.

13. In a perforating machine the combination of a finger key and a punch, a punch lever, an electrically operated power mechanism arranged in a normally open circuit, circuit closing means normally controlled by the key to close the circuit, an interposing member connected adjacent one of its ends to the key and having its other end connected by a pin and fork connection to the punch lever and lying outside the path of movement of the power mechanism and adapted to receive from the key an endwise movement whereby the punch lever connected end of the interposing member will be moved into a position intermediate the punch lever and the power mechanism where it will receive movement from the power mechanism independently of the key upon the depression of the key and thereby operate the lever that operates the punch; said power mechanism being adapted when operated to release the circuit closing means from its key control in advance of any return movement of the key toward its normal position of rest.

14. In a perforating mechanism the combination of a finger key and a punch, a punch lever, an electrically operated power mechanism arranged in a normally open circuit, circuit closing means controlled by the key to close the circuit, an interposing member connected adjacent one of its ends to the key and having its other end operatively connected to the punch lever and normally outside the path of movement of the power mechanism and adapted to receive from the key an endwise movement whereby the punch lever connected end of the interposing member will be moved into position where it will receive movement from the power mechanism independently of the key upon the depression of the key and op-

- erate the lever which operates the punch; and means operated by the power mechanism for breaking the mechanical connection between the key and the circuit closing means immediately after the actuation of the punch and in advance of any return movement of the key toward its normal position of rest.
15. In a key controlled mechanism the combination of a key, an operated part, a lever associated with the operated part for actuating it, an electrically operated power mechanism controlled by the key, said electrically operated power mechanism comprising an electro-magnet arranged in a normally open circuit, a motor plate actuated by said magnet, a circuit closer in said circuit comprising two resilient contact members normally spaced apart, an interposing member connected to said key and adapted to be moved endwise into position to be struck by the motor plate, the key being adapted to impart movement to the interposing member whereby it will be moved endwise into position to be struck by the motor plate, and means operated by the key to close the circuit; the motor plate being adapted to disconnect the key from the circuit closing means in advance of the release 30 of the key.
16. In a key controlled mechanism the combination of a key, an operated part, a lever associated with the operated part for actuating it, an electrically operated power mechanism controlled by the key, said power mechanism comprising a magnet arranged in a normally open circuit, a motor plate operated by said magnet, a circuit closer in said circuit comprising two resilient contact members normally spaced apart, an interposing member connected to said key and adapted to be moved endwise into position to be struck by the motor plate; the key being adapted to impart movement to the interposing member whereby it will be moved endwise into position to be struck by the motor plate, a contact arm having one of its ends releasably connected with one of the contact members and means operated by the key to operate the arm to close the contacts; said motor plate being adapted when operated to disconnect said arm from the contacts.
17. In a key controlled mechanism the combination of a key, an operated part, a lever associated with the operated part for actuating it, an electrically operated power mechanism controlled by the key, said electrically operated power mechanism comprising a magnet arranged in a normally open circuit, a motor plate actuated by said magnet, a circuit closer in said circuit comprising two resilient contact members normally spaced apart, an interposing member connected to said key and adapted to be moved endwise into position to be struck by the motor plate, the key being adapted to impart movement to the interposing member whereby it will be moved endwise into position to be struck by the motor plate, a contact arm having one of its ends releasably connected with one of the contact members and means operated by the key to operate the arm to close the contacts; said motor plate being adapted when operated to disconnect said arm from the contacts.
18. In a key controlled mechanism the combination of a plurality of finger keys, a plurality of operated parts one for each key, a lever associated with each of the operated parts for operating it, an electrically operated power mechanism controlled by the key, said electrically operated power mechanism including a magnet arranged in a normally open circuit, a motor plate operated by the magnet, a circuit closer in said circuit comprising two resilient contact members normally spaced apart, a contact frame adapted to be operated by the keys each as required, a contact arm releasably connected with one of said contact members and operated by the contact frame upon the depression of any of said keys, an interposing member connected to each of said keys one for each key, and adapted to be moved into position to be struck by the motor plate, each of said keys being adapted to move its interposing member into position to be struck by the motor plate, and each of said keys upon its depression operating also the contact frame and thereby causing the contact arm to close the contacts, said motor plate being adapted when operated to disconnect the contact arm from the contacts.
19. In a perforating machine, the combination with suitable supports of a plurality of punches, a plurality of finger keys there being a finger key for each punch, a lever associated with each punch for actuating it, an electrically operated power mechanism including an electro-magnet arranged in a normally open circuit, a motor plate actuated by said magnet, a circuit closer in said circuit including a resilient contact member, a contact frame adapted to be operated by the keys each as required, a contact arm releasably connected with one of said contact members and operated by the contact frame upon the depression of any of said keys, an interposing member connected with each of said keys one for each key and adapted to be moved into position to be struck by the motor plate, each of said keys being adapted to move its interposing member into position to be struck by the motor plate, and each of said keys upon its depression operating also the contact frame and thereby

causing the contact arm to close the contacts, said motor plate when operated also releasing the contact member from the contact arm.

5 20. In a key controlled mechanism the combination of a finger key, an operated part, a lever associated with the operated part for actuating it, an electrically operated power mechanism interposed between 10 said lever and key, comprising a normally open circuit, including a magnet, a motor plate arranged to be actuated by said magnet, two resilient contact members normally spaced apart in the circuit, an interposing 15 member in operative connection with the key and adapted to be moved endwise by the key into the path of movement of the motor plate, and the key being adapted to impel the interposing member in an endwise 20 movement into the path of movement of the motor plate, and means operated by the key to close the circuit; said motor plate being also adapted to release the circuit closing means from its key control in advance 25 of any return movement of the key toward its normal position of rest.

21. In a perforating machine the combination of a base having guideways, a card carrier movable along the guideways, a 30 punch support rigidly secured to the base near its center, the punch support having a series of sockets extending across it transversely to the path of movement of the card carrier, a spring supported punch located 35 in each of said sockets, a plate having dies registering with the punches there being a space between the die plate and the punches for permitting the passage therethrough of the card to be punched, a plurality of finger 40 keys, a normally inactive motor, means normally controlled by the finger keys for causing the motor to be actuated, means controlled by the motor for advancing the card carrier along the guideways, means movable 45 independently of the finger keys, operated by the motor, for actuating the punches each as required, and for disconnecting the motor controlling means from the finger key in advance of any return movement of the finger 50 key toward its normal position of rest, thereby permitting the motor to be rendered again inactive immediately after once having actuated the punch.

22. In a card perforating machine the combination of a base, a movable card carrier, a punch support having a series of sockets extending across it transversely to the path of movement of the card carrier, spring supported punches in the sockets one 60 in each socket, a stationary plate having dies registering with the punches, a plurality of levers all of even length associated with the punches for operating them there being a lever for each punch, a fulcrum plate suitably supported and extending across the 65

path of movement of the card carrier and equi-distant from all the punches and having an edge adapted to act as a pivot or fulcrum for the levers, said levers being adapted at one of their ends to engage the 70 edge of said fulcrum plate and to be so connected with the punches that a movement of the other or power end of the levers will cause them to operate the punches each as required, a plurality of finger keys, a normally inactive motor, means normally controlled by the finger keys to cause the motor to operate, means controlled by the motor for advancing the card carrier by a step by step movement, means movable independently of the finger key, operated by the motor, for operating the levers which operate the punches and for disconnecting the motor controlling means from the finger key in advance of any return movement of the 80 finger key toward its normal position of rest, thereby permitting the motor to be again rendered inactive in advance of any return movement of the finger key toward its normal position of rest, said motor thenceforth 85 remaining inactive until another key depression.

23. In a perforating machine the combination of a base having guideways, a card carrier movable along the guideways, suitable feeding and escapement means for advancing the card carrier by a step by step movement along the guideways, a punch support having a series of sockets extending across it transversely to the path of movement of the card carrier, spring supported punches in the sockets one in each socket, a plate having dies registering with the punches, a plurality of levers all of even length associated with the punches for operating them there being a lever for each punch, a fulcrum plate, suitably supported, extending across the path of movement of the card carrier and having an edge equally distant from all the punches and adapted to 100 act as a pivot or fulcrum for all said levers, each of said levers being adapted adjacent one of its ends to engage the edge of said fulcrum plate and to be so connected with the punches that a movement of the other 105 or power end of the levers, each as required, will cause it to operate its corresponding punch; an electrically operated power mechanism arranged in a normally open circuit, a plurality of finger keys, circuit closing means arranged to be operated by the keys to close the circuit to actuate the power mechanism, means movable independently of the movement of the keys, operated by the power mechanism, for operating the punch 110 actuating levers and for permitting the card carrier to be advanced a predetermined distance and for releasing the circuit closing means from its finger key control, the power mechanism thereupon becoming again inactive.

tive in advance of any return movement of the finger key toward its normal position of rest.

24. In a perforating machine the combination of a base having guideways, a card carrier, suitable feeding and escapement mechanism for advancing the card carrier by a step by step movement along the guideways, a punch support having a series of 10 sockets extending across it transversely to the path of movement of the card carrier, spring supported punches in the sockets one in each socket, a plurality of levers all of equal length resting upon the punches for 15 operating them there being a lever for each punch, a fulcrum plate suitably supported and extending across the path of movement of the card carrier and having an edge equally distant from all the punches and 20 adapted to act as a pivot or fulcrum for all the punch actuating levers aforesaid; each of said levers being adapted adjacent one of its ends to engage the edge of said fulcrum plate and to be so associated with the 25 punches that a movement of the other or power end of the levers each as required will cause the lever to operate its corresponding punch; an electrically actuated power mechanism arranged in a normally 30 open circuit, a link connecting the power mechanism with the escapement mechanism, a plurality of finger keys, circuit closing means operated by the finger keys each as required to close the circuit to actuate the 35 power mechanism, means movable independently of the movement of the finger key, operated by the power mechanism, to actuate the levers and to release the circuit closing means from its key control, whereupon the 40 power mechanism becomes deenergized and returns to its normal position of rest in advance of any return movement of the finger key toward its normal position of rest.

25. The combination of a motor plate, a 45 motor for operating the motor plate, a series of punches, a series of punch actuating levers each operatively connected adjacent one of its ends with one of the punches to operate it and each of the levers provided 50 at its other end with a push finger, the push fingers being pivoted to the levers and having their free ends normally out of the path of movement of the motor plate, a series of finger keys, means operated by the finger 55 keys for bringing the free ends of the push fingers into the path of movement of the motor plate, and means operated by a movement of the finger keys to cause the motor to operate.

26. The combination of a motor plate, a 60 motor for operating the motor plate, a series of punches, a series of punch actuating levers, each of said levers operatively connected adjacent one of its ends to its 65 respective punch to operate it and each of the

levers provided at its other end with a push finger, the push fingers being pivoted to the levers and having their free ends normally out of the path of movement of the motor plate; a series of finger keys having springs 70 associated with them for returning them when displaced to their normal position of rest, means operated by the finger keys for bringing the free ends of the push fingers into the path of movement of the 75 motor plate, means operated by a movement of the finger keys, each as required, to cause the motor to operate; each of said finger keys being adapted to restore its respective push finger to its normal position of rest 80 upon the release of the finger key.

27. The combination of a series of punches, a series of finger keys one for each punch, an electrically operated power mechanism controlled by said keys, said power 85 mechanism comprising an electro-magnet arranged in a normally open circuit, a motor plate actuated by said magnet, a circuit closer in said circuit comprising two contact members normally spaced apart; one of said 90 contact members having a normal position to which it tends to return when displaced, a contact frame operated by all of said keys each as required and a contact arm co-acting with the contact frame upon the depression 95 of a key to close the contacts; a series of punch actuating levers, each operatively connected adjacent one of its ends with its respective punch to operate it and each of said levers provided at its other end with a 100 push finger, the push fingers being pivoted to the levers and having their free ends normally out of the path of movement of the motor plate, means operated by the finger keys for bringing the free ends of the push 105 fingers into the path of movement of the motor plate; said motor plate being adapted, when actuated by the power mechanism upon the depression of a key, to operate all of said push fingers each as required and 110 therethrough to operate the punch actuating levers and the punches, and to disconnect the contacts from their key control, whereupon the contacts separate and the motor is deenergized after once having operated the 115 motor plate, in advance of the return movement of either the finger key or the contact frame toward its normal position of rest.

28. In a perforating machine the combination of a punch, a pivoted lever, a finger 120 key, means for returning said key when displaced to its normal position of rest, a normally inactive motor, a motor plate operated by the motor; said lever being operatively connected adjacent one of its ends 125 with the punch to operate it and provided adjacent its other end with a push finger, the push finger being pivoted to the lever and having its free end normally out of the path of movement of the motor plate, means 130

operated by the key for moving the free end of the push finger into the path of movement of the motor plate, means controlled by the key to cause the motor to operate the motor plate to effect movement of the punch actuating lever and to disconnect the said motor controlling means from the key, whereupon said motor controlling means resumes its normal position and the motor thereupon becomes inactive in advance of the release of the key and remains inactive till another key depression.

29. In a perforating machine the combination of a finger key and means associated with it for restoring it when displaced to its normal position of rest, a normally inactive motor, a motor plate actuated by the motor, a punch, a punch actuating lever, a push finger pivoted to the lever, a slideable bar connecting the push finger to the key, said key having integral with it an extension serving as a cam to transmit reciprocal motion in a plane other than that of the key to the bar, said bar being suitably supported and in engagement with said key extension and adapted to be moved thereby upon the depression of the key and also to move the free end of the push finger into the path of movement of the motor plate to receive movement therefrom independently of the key and to transmit motion so received to the punch actuating lever; means normally controlled by the key to cause the motor to operate the motor plate, the motor plate thereupon operating the push finger and disconnecting the motor controlling means from the finger key, thus permitting the motor controlling means automatically to return toward its normal position of rest and thereby to deenergize the motor after its having once actuated the motor plate and the motor becomes thereupon again inactive in advance of any return movement of the finger key toward its normal position of rest, and remains inactive till another key depressing.

30. In a key controlled mechanism the combination of a finger key, a spring associated with the key for restoring it when displaced to its normal position of rest, an operated part, a normally inactive motor, a motor plate actuated by the motor, means controlled by the key for causing the motor to be actuated, a push finger, a slideable bar connecting the push finger with the key and adapted to receive motion therefrom, one end of the push finger being normally free and out of the path of movement of the motor plate; the key being adapted upon its depression to impart to the bar an endwise sliding motion, thereby impelling the bar and therethrough the push finger into a position between the motor plate and the operated part where the push finger will receive

movement from the motor plate independently of the key and impart motion so received to the operated part; said motor plate being adapted, when operated by the motor, to disconnect the motor controlling means from the key after one operation of the operated part, in advance of any return movement of the finger key toward its normal position of rest.

31. In a key controlled mechanism the combination of a finger key, a spring associated with the key for restoring it when displaced to its normal position of rest, an operated part, a normally inactive motor, a motor plate operated by the motor, means controlled by the key for causing the motor to be actuated, a slideable bar connected to the key and adapted to receive motion therefrom, a push finger pivoted to the lever and operatively connected to the bar and having one of its ends normally free and out of the path of movement of the motor plate; said key being adapted upon its depression to impart to the bar an endwise sliding motion, thereby impelling the free end of the push finger into a position between the motor plate and the operated part where the push finger will receive motion from the motor plate independently of the key and impart motion so received to the operated part; the motor plate having integral with it an extension for disconnecting the finger key from the motor controlling means upon the operation of the motor immediately after the operation of the operated part, thus permitting the motor controlling means to return to its normal position of rest in advance of any return movement of the key toward its normal position of rest; said key being adapted to again restore the push finger to its normal position of rest upon the release of the key.

32. In a perforating machine the combination of a finger key, means for restoring the key when displaced to its normal position of rest, a punch, a punch actuating lever, a push finger, a normally inactive motor, a motor plate actuated by the motor, means controlled by the key for causing the motor to be actuated, a slideable bar suitably supported above the finger key and operatively connected to the push finger and also connected to the key and adapted to receive an endwise sliding motion from the key, one end of the push finger being normally free and out of the path of movement of the motor plate; said key being adapted upon its depression to impart to the bar an endwise sliding motion, thereby impelling the free end of the push finger into a position between the motor plate and the punch actuating lever where the push finger will receive motion from the motor plate independently of the key and operate the

lever which operates the punch; the motor plate immediately thereafter disconnecting the motor controlling means from the key and the motor becomes deenergized in advance of the release of the key.

33. In a perforating machine the combination of a finger key, a punch, a punch actuating lever, a push finger pivoted to the lever, a normally inactive motor, a motor plate operated by the motor, means controlled by the key for causing the motor to be actuated, a slidable bar in engagement with the key and adapted to receive an endwise sliding motion therefrom and being also connected with the push finger, one end of the push finger being normally free and out of the path of movement of the motor plate; said key being adapted upon its depression to impel the push finger through its bar connection into a position where it will be moved by the motor plate independently of the key and impart motion so received to the punch actuating lever to operate the punch; the motor plate thereupon disconnecting the finger key from said motor controlling means in advance of any return movement of the key toward its normal position of rest and the motor thereupon becomes deenergized.

34. In a perforating machine the combination of a finger key, a spring associated with said key for restoring it when displaced to its normal position of rest, a punch, a punch actuating lever, a push finger, a normally inactive motor, a motor plate operated by the motor, means controlled by the key for causing the motor to be actuated, a bar slidably supported adjacent its two ends upon suitable supports and extending across the plane of movement of the key and in engagement with the key and adapted to receive motion therefrom, said push finger having one of its ends normally free and out of the path of movement of the motor plate; said key being adapted upon its depression to impart to the bar an endwise sliding motion, thereby impelling the free end of the push finger into a position between the motor plate and the punch actuating lever, where the push finger will receive movement from the motor plate independently of the key and impart motion so received to the lever to actuate the punch; the motor plate being also adapted, when operated by the motor, to disconnect the key from the motor controlling means in advance of any return movement of the key toward its normal position of rest.

35. In a perforating machine the combination of a finger key, a spring associated with said key for restoring it when displaced to its normal position of rest, a punch, a punch actuating lever, a push finger pivoted to the lever, a normally inactive motor,

a motor plate actuated by the motor, means controlled by the key for causing the motor to be actuated, a slidable bar suitably supported and extending across and above the key, said key having an extension integral with it and in engagement with the bar adjacent their lines of intersection and adapted upon the depression of the key to move the bar and therethrough to move the push finger into a position between the motor plate and the punch actuating lever, where the push finger will receive movement from the motor plate independently of the key and impart motion so received to the lever to actuate the punch; said motor plate having integral with it an extension for disconnecting the key from the motor controlling means in advance of any return movement of the key toward its normal position of rest, whereupon said motor will immediately become inactive till another key depressing said key extension being also adapted, upon the release of the key to restore both the bar and the push finger to their respective normal positions of rest.

36. In a key controlled mechanism the combination of a finger key and an operated part, an electrically operated power mechanism arranged in a normally open circuit, circuit closing means operated by the key to close the circuit, a push finger, a slidable bar connecting the push finger to the key, one end of the push finger being normally free and out of the path of movement of the power mechanism, said bar being adapted to be given an endwise movement by the key and thereby to move the free end of the push finger into a position where it will receive motion from the power mechanism independently of the key and transmit motion so received to the operated part; said power mechanism being also adapted to disconnect the key from the circuit closing means in advance of any return movement of the key toward its normal position of rest.

37. In a perforating machine the combination of a finger key and a punch, a punch lever, a push finger pivoted to the lever, an electrically operated power mechanism arranged in a normally open circuit, circuit closing means normally controlled by the key to close the circuit, a slidable bar connected adjacent one of its ends to the key and having its other end in operative connection with the push finger, one of the ends of the push finger being normally free and outside the path of movement of the power mechanism, the bar being adapted to receive from the key an endwise movement whereby the free end of the push finger will be moved into a position intermediate the punch lever and the power mechanism where it will receive movement from the power mechanism independently of the key upon

the depression of the key and thereby operate the lever that operates the punch; said power mechanism being adapted when operated to release the circuit closing means from its key control in advance of any return movement of the key toward its normal position of rest.

38. In a perforating mechanism the combination of a finger key and punch, a punch lever, a push finger pivoted to the lever, an electrically operated power mechanism arranged in a normally open circuit, circuit closing means controlled by the key to close the circuit, a slidable bar connected adjacent one of its ends to the key and having its other end in operative connection with the push finger, one end of the push finger being normally free and outside the path of movement of the power mechanism, the bar being adapted to receive from the key an endwise movement whereby the free end of the push finger will be moved into a position where it will receive movement from the power mechanism independently of the key upon the depression of the key and thereby operate the lever which operates the punch; and means operated by the power mechanism for breaking the mechanical connection between the key and the circuit closing means immediately after the actuation of the punch and in advance of any return movement of the key toward its normal position of rest.

39. In a key controlled mechanism the combination of a key, an operated part, a lever associated with the operated part for actuating it, an electrically operated power mechanism controlled by the key, a push finger pivoted at one end to the lever and having its other end normally outside the path of movement of the power mechanism, said power mechanism comprising an electro-magnet arranged in a normally open circuit, a motor plate operated by the magnet, a circuit closer in said circuit comprising two resilient contact members normally spaced apart, a slidable bar connected to said key and adapted to be moved endwise thereby, the bar being also operatively connected to the push finger and adapted to move the push finger upon a depression of the key into a position to be struck by the motor plate, the key being adapted to impart movement to the bar and therethrough to the push finger whereby the push finger will be moved into a position to be struck by the motor plate, and means operated by the key to close the circuit; the motor plate being adapted to disconnect the key from the circuit closing means in advance of the release of the key.

40. In a key controlled mechanism the combination of a key, an operated part, a lever associated with the operated part for

actuating it, a push finger pivoted to the lever, an electrically operated power mechanism controlled by the key, said power mechanism comprising a magnet arranged in a normally open circuit, a motor plate actuated by said magnet, a circuit closer in said circuit comprising two resilient contact members normally spaced apart, a slidable bar connected to the key and adapted to move the push finger into position to be struck by the motor plate, the key being adapted to impart movement to the bar and therethrough to move the push finger into position to be struck by the motor plate, a contact arm having one of its ends releasably connected with one of the contact members and means operated by the key to operate the arm to close the contacts; said motor plate being adapted when operated to disconnect said arm from the contacts.

41. In a key controlled mechanism the combination of a key, an operated part, a lever associated with the operated part for actuating it, a push finger pivoted to the lever and having one of its ends normally free, an electrically operated power mechanism, controlled by the key, said electrically operated power mechanism comprising a magnet arranged in a normally open circuit, a motor plate operated by said magnet, a circuit closer in said circuit comprising two resilient contact members normally spaced apart, a slidable bar operatively connected to said key and adapted to be moved endwise upon a movement of the key, the key being adapted to impart movement to the bar whereby it will be moved endwise and thereby move the push finger into position to be struck by the motor plate, a contact frame operated by the key and a contact arm connected with and operated by the contact frame and adapted to close the contacts upon a depression of the key, said motor plate being adapted when actuated to release the contact member from its contact arm control in advance of any return movement of the contact frame toward its normal position of rest.

42. In a perforating machine, the combination of a base having guideways, a card carrier movable along the guideways, a punch support rigidly secured to the base and having a series of sockets extending across it transversely to the path of movement of the card carrier, spring-supported punches in the sockets one in each socket, means for operating the punches each as required, suitable feeding and escapement mechanism controlled by the punch-operating means for advancing the card carrier by a step-by-step movement along the guideways, whereby the card to be punched is brought within the range of action of the punches, an index card carried by a frame

co-acting with the card carrier, and a stationary indicator rigidly secured to the frame of the machine and so associated with the index card as that the then position of the card being perforated in its relation to all the punches will be indicated upon the index card.

In testimony whereof, I affix my signature in the presence of two witnesses.

JOHN THOMAS SCHAAFF.
